MAGNETOELECTRIC SHOCKING DEVICE

James Trotta, New York, N. Y.

Application August 29, 1950, Serial No. 182,055

5 Claims. (Cl. 315—218)

1

This invention relates to new and useful improvements in magnetoelectric shocking devices.

One object of the present invention is to provide in a magnetoelectric shocking device novel means for affecting the magnetic field thereof to thereby affect the shocking quality of the device.

Another object of the present invention is to provide with a magnetoelectric shocking device means interchangeably utilized therewith and whereby the normal current pulsations may be increased to thereby facilitatedly adapt same for a variety of uses.

Another object of the present invention is to provide a magnetoelectric shocking device which is so constructed that when utilized for operating therapeutic devices it may be initially set up so that a certain shocking quality, and none higher, may be obtained therefrom, thereby preventing bodily injuries by one's ignorance of the potentialities of such devices.

Another object of the present invention is to provide a magnetoelectric shocking device of such construction that same may be facilitatedly disabled to prevent operation thereof by any unauthorized persons.

Still another object of the present invention is to provide with a magnetoelectric shocking device a plurality of horseshoe magnets which may be interchangeably and combinationally utilized therewith in order to affect the shocking quality of the device.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a plan view of the device of the invention.

Fig. 2 is a front elevational view of the device.

Fig. 3 is a right-hand side elevational view.

Fig. 4 is an elevational view of the interrupter, per se.

Fig. 5 is a fragmentary view of the device constructed in accordance with a modification of the present invention.

Fig. 6 is an elevational view of a modified form of interrupter.

Fig. 7 is a diagram illustrating the wiring of the device.

The magnetoelectric shocking device, according to the first form of the invention shown in Figs. 1 to 4, includes an armature housing 10, which comprises magnetic front and rear members 11 and 12, respectively, and non-magnetic left and right side members 13 and 14, respectively, all of which are mounted on a wooden base 15. Provided for being turned in said housing on trundles 16 and 17 which are journaled in and

2

extend through the respective ones of the side members 13 and 14 is an armature 18.

Secured on the right trundle 17 just outwardly of the right side member 14 is a spur gear 19 which meshes with and is driven by a gear 20 fast on a drive shaft 21 journalled between the side members 13 and 14. Said drive shaft 21 is arranged to be rotated manually by a crank 22 secured to the right hand extremity thereof.

Threadedly carried on the extremity of the right trundle 17 and maintained secure thereon by a knurled nut 23 is an interrupter 24 which comprises a current conductive disc 25, an insulative disc 26, and a plurality of contact points 27 passing through said insulative disc from the conductive disc.

Provided to cooperate resiliently with the contact points 27 is a leaf spring 28, which spring is attached to a conductive lug 29 mounted on the base 15 and having an electrical terminal 30.

Secured on the extremity of the left-hand trundle 16 is a commutator 31. A leaf spring 32 secured to a conductive lug 33 mounted on the base 15 is arranged to cooperate with the commutator 31. Also, secured in the lug 33 is a terminal 34.

Mounted on the base 15 at the left side end thereof is an upright member 35. Secured atop the upright member 35 is an electric light 36 having terminals 37 and 38. A wire 39 interconnects the terminal 37 with the aforementioned terminal 34 and another wire 40 interconnects the terminal 38 with the other aforementioned terminal 30.

Fitted in the upright member 35 is a plug 41 having terminals 42 and 43. A wire 44 interconnects the terminal 42 with the terminal 34 and another wire 45 interconnects the terminal 43 with the terminal 30.

Now, provided with the present arrangement is a permanent horseshoe magnet 46 which is such that it may be simply placed on the front and rear members 10 and 11 when the device is to be utilized and may be removed when it is to be disabled.

The just described arrangement is such that turning of the crank 22 effects the induction of a current in the armature 18. This current is taken off the commutator 31 by the spring 32. Thereafter the current is delivered by the wires 39 and 44 to the light 36 and the plug 41, respectively.

Now, with reference to Fig. 7 also, it is to be seen that the interrupter contact points 27 are ground and before the circuits through the light and plug are complete the spring 28 must make contact with said points. Also, the current induced in the armature is normally of a pulsating nature. This pulsating current will be interrupted still further by the turning of the interrupter and will be much more suitable for the

operation of certain therapeutic and other devices.

It will be seen that the mentioned light 36 will blink or flash on and off in accordance with both the normal pulsations of the induced current and the pulsations effected by the mentioned interrupter. Thusly, an operator may visually ascertain the shocking quality of the current being produced and knowing such may turn the crank 22 at a rate of speed in accordance with a desired quality to be obtained.

Further, the described arrangement is desirable in that a magnet of any prescribed strength may be employed therewith when the device is setup to assure against the provision of a shocking effect greater than that of a prescribed quality. Also, the device may be disabled simply by removing the magnet, and in this way its operation by unauthorized persons is prevented.

As seen in Fig. 5, a plurality of magnets 50 may be utilized separately or combinationally with the present device and in this way the shocking quality may be further affected to be in accordance with a prescribed need.

As seen in Fig. 6, a modified form of interrupter 53 provides both circular contact points 54 and elongated contacts 55. This modification alters the normal pulsating of the current in a dual manner and renders it more applicable to certain other uses.

It will be seen that the interrupter contacts may be disposed thereon in any desired arrangement in order to provide any desired alterations of the normal magnetoelectric pulsations induced in the device.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a magnetoelectric device of the class described, a manually rotative armature having end aligned rotatively supported trundles, a commutator mounted on one of said trundles, a contact terminal having a leaf spring engaging said commutator, a current conductive disc mounted on the other of said trundles, an insulative disc mounted on the said other trundle in face contact with said conductive disc, contact points extending from the face of said conductive disc engaging said insulative disc and through said insulative disc, said contact points being arranged in a circle concentric with the axis of rotation of the said other disc and exposed on the face of said insulative disc facing away from said conductive disc, and a contact terminal having a leaf spring engaging said insulative disc to successively engage said contact points as said armature is rotated.

2. In a magnetoelectric device of the class described, a manually rotative armature having end aligned rotatively supported trundles, a commutator mounted on one of said trundles, a contact terminal having a leaf spring engaging said commutator, a current conductive disc mounted on the other of said trundles, an insulative disc mounted on the said other trundle in face contact with said conductive disc, contact points extending from the face of said conductive disc engaging said insulative disc and through said

insulative disc, said contact points being arranged in a circle concentric with the axis of rotation of the said other disc and exposed on the face of said insulative disc facing away from said conductive disc, and a contact terminal having a leaf spring engaging said insulative disc to successively engage said contact points as said armature is rotated, at least one of said contact points being arcuate in form.

10 3. In a magnetoelectric device of the class described, a manually rotative armature having end aligned rotatively supported trundles, a commutator mounted on one of said trundles, a contact terminal having a leaf spring engaging said commutator, a current conductive disc mounted on the other of said trundles, an insulative disc mounted on the said other trundle in face contact with said conductive disc, contact points extending from the face of said conductive disc engaging said insulative disc and through said insulative disc, said contact points being arranged in a circle concentric with the axis of rotation of the said other disc and exposed on the face of said insulative disc facing away from said conductive disc, and a contact terminal having a leaf spring engaging said insulative disc to successively engage said contact points as said armature is rotated, at least one of said contact points being arcuate in form.

20 4. In a magnetoelectric device of the class described, a manually rotative armature having end aligned rotatively supported trundles, a commutator mounted on one of said trundles, a contact terminal having a leaf spring engaging said commutator, a current conductive disc mounted on the other of said trundles, an insulative disc mounted on the said other trundle in face contact with said conductive disc, contact points extending from the face of said conductive disc

30 5. In a magnetoelectric device of the class described, a manually rotative armature having end aligned rotatively supported trundles, a commutator mounted on one of said trundles, a contact terminal having a leaf spring engaging said commutator, a current conductive disc mounted on the other of said trundles, an insulative disc mounted on the said other trundle in face contact with said conductive disc, contact points extending from the face of said conductive disc engaging said insulative disc and through said insulative disc, said contact points being arranged in a circle concentric with the axis of rotation of the said other disc and exposed on the face of said insulative disc facing away from said conductive disc, and a contact terminal having a leaf spring engaging said insulative disc to successively engage said contact points as said armature is rotated, said contact points being alternately arranged circular and elongated contact points, said elongated contact points being arcuate concentric with the circle formed by said contact points.

40 6. A magnetoelectric device in accordance with claim 1 in which a lamp is electrically connected in parallel with both contact terminals to flash in accordance with the current pulsations produced in said device whereby visual indication is given to the shocking quality of the current pulsations.

50 JAMES TROTTA.
